UNITED STATES PATENT OFFICE

92,351

DESIGN FOR A THERMO-REGULATOR

Valentine Hiergesell, Philadelphia, Pa., assignor
by mesne assignments, to H-B Instrument Co.,
Inc., Philadelphia, Pa., a corporation of Penn-
sylvania

Application October 11, 1932, Serial No. 45,316

Term of patent 14 years

To all whom it may concern:

Be it known that I, VALENTINE HIERGESELL, a citizen of the United States, residing at Philadelphia, in the county of Philadelphia, and State of Pennsylvania, have invented a new, original, and ornamental Design for a Thermo-Regulator, of which the following is a specification, reference being had to the accompanying drawings, forming part thereof.

Figure 1 is a view in side elevation of a thermo-regulator, showing my new design;

Figure 2 is a top plan view thereof, and

Figure 3 is a sectional view thereof.

I claim:

The ornamental design for a thermo-regulator, as shown.

VALENTINE HIERGESELL.
